UNITED STATES PATENT OFFICE

2,509,817

GAS SEPARATOR

George L. Foreman, Los Angeles, Calif.

Application April 23, 1948, Serial No. 22,791

5 Claims. (Cl. 183—21)

1

This invention relates to purifying smoke and removing solid matter entrained therein and a primary object of the invention is to saturate a gas such as smoke with fluid until solid particles therein will become heavy enough to separate from the carrying agent to fall by gravity, for subsequent reclaiming or disposal.

Another object of the invention is to cause the gas or smoke to enter a separating device tangentially and to continue in a spiral path of travel to increase the length of contact time for the gas with a solid removing vapor until the maximum amount of solids have been separated therefrom and the gas is removed free of solid impurities.

And another object of the invention is to provide a dense fog of liquid that will envelop and cool entrained solid particles in a gas until such saturation as will overcome the buoyancy thereof with a subsequent separation, the heavier solids falling due to the action of gravity and the lighter gas escaping from the combining space.

And still another object of the invention is to provide a continuous process for the separation of solids in gases.

A further object of the invention is to provide a separating chamber with means to induce a spiral travel for contaminated materials to separate solids from the carrying means.

And a further object of the invention is to provide a separator that is readily assembled and dismantled when necessary for purposes of cleaning or storage or the like.

And still a further object of the invention is to provide a gas washer capable of handling a maximum volume of gas for a given weight of column and with a relatively high efficiency, and a structure that is simple but durable in construction and economical in manufacture.

In addition to the above, the invention comprehends improvements in details of construction and arrangement of parts to be hereinafter described and set forth in the claims.

In the following drawings, in which similar and corresponding parts are designated by the same reference characters throughout the several views,

Figure 1 is a side elevation of the gas separating device;

Figure 2 is a top plan view of the device of Figure 1;

Figure 3 is a vertical sectional view and is taken substantially on the line 3—3 of Figure 2;

2

Figure 4 is a horizontal sectional view and is taken substantially on the line 4—4 of Figure 3, and

Figure 5 is a horizontal sectional view and is taken substantially on the line 5—5 of Figure 3.

Referring to the figures, the gas separator of the invention is indicated generally by numeral 10 and includes an outer chamber or cylinder 12, and an inner cylinder or chamber 14. Outer chamber 12 is entirely enclosed except for an inlet conduit 16 entering tangentially, as is clearly seen in Figure 2, at the upper surface thereof. Gas outlet means are provided on the top integral cover 18 through which inner cylinder 14 extends 15 and is suitably secured thereto by means of an annular flange or plate 20 and bolted thereto by suitable bolt means 22. Cylinder 12 includes a convex bottom 24 secured to the side thereof by retaining bolts 26. An outlet 28 for removed 20 solids and liquids is provided axially of chamber 12 in bottom 24. While bottom 24 has been shown as convexly constructed, it is to be understood that any suitable type of removal means may be provided, such as a frusto-conical outlet.

25 Inner chamber 14 is of hollow construction and is open at both ends, for a purpose soon to become apparent. A spiral baffle 30 is mounted within the space between the annular area defined by cylinders 12 and 14 and terminates at the 30 upper end thereof adjacent the point of entry of tangential conduit 16 and extends in spiral design to a point adjacent the bottom of cylinder 12. Thus, it is readily apparent that smoke or other gases containing entrained particles to be separated therefrom will be forced under pressure, by suitable means not shown, into conduit 16 to enter chamber 12 in a circular path of travel. The gases will continue in a spiral, downward path through the length of the chamber 35 guided by spiral means 30 while entrained solids are separated therefrom, in a manner presently to become apparent. Inner cylinder 14 includes a similar spiral baffle 32 secured to a fluid carrying pipe 34. Spiral 32 terminates in lateral 40 flange members 35 containing depending ears 36 and are adapted to seat in the U-shaped retaining clip 38 at the base of cylinder 14. It is to be noted here that inner chamber 14 is suspended a short distance above bottom 24 of cylinder 12 to 45 enable a sharp separation between entrained solids and gases to take place.

A plurality of saturating pipes 40, of which four in number are employed, extend in parallel relation with the outer periphery of cylinder 12 50 and are bent over the cover 18 and are joined

by a cross coupling 42. At various intervals along the vertical length thereof are mounted branch pipes 44 terminating in spray nozzles 46, and so constructed that they face in the path of travel of the spirally moving gases. Suitable valves 47 control the flow of fluid to nozzles 46. Pipe 34 is also secured to coupling member 42 by means of a depending nipple 48 and extends axially within inner chamber 14. A number of spray nozzles 50 are mounted laterally at the lower end of pipe 34. Spray conduits 49 are sectional in construction and include coupling members 52 on the upper outer surface thereof for dismantling when it is desirable to remove pipes 46 and inner pipe 34 and spiral baffle 32 for purposes of cleaning or storage. Pipes 46 and spray pipes 44 enter cylinders 12 and 14 through suitable bearings 54 on the outer peripheries of chambers 12 and 14.

In operation, smoke or other gases saturated with entrained solids are forced into chamber 12 through conduit 16, and impinge on the inner walls thereof. The downward travel thereof in spiral baffle 30 cause the gases to be assured a maximum time of contact with fog spray emitted through nozzles 46. Since nozzles 46 enter at four points within chamber 12, complete saturation of the solids entrained in the gases is assured, and as a result, when these solids have reached the lowermost point of travel in the outer chamber, they will have completely separated from the carrying medium to drop into bottom 24 for removal with condensed water through outlet 26. The gases, now purified, will reverse their path of travel and move upwardly through inner chamber 14 in a spiral path induced by baffle 32. Spray nozzles 50 are mounted in the lower portion of chamber 14 to separate out any final solid particles that may have been carried along by the escaping gases. Any moisture carried by the escaping gases is now condensed on the upper portion of chamber 14 for return to the bottom of cylinder 12. Spiral separating means 32 and 34 are of particular help in effecting such separation since they are constantly wet from the fog-like spray emitted through nozzles 46, and as a result, all solids that come in contact with the spiral baffles adhere thereto and are separated from the gases. The shape of nozzles 46 does not interfere with the travel of the gases, but actually assists such rotary movement. While there is a slight clearance between inner spiral 32 and the inner surface of chamber 14, the fog-like spray emitted through nozzle 50 effectively seals the opening and prevents smoke or gas from escaping. For best performance, the area of the spiral baffles is about twice the area of the intake means.

Any suitable material may be employed in the construction of the gas separator. As many modifications of the embodiment above illustrated might be made without departing from the spirit or scope of the invention, and it is intended that the above description and accompanying drawings and claims shall be interpreted as illustrative and not in a limiting sense.

Having described the invention, what is claimed as new is:

1. A gas separator consisting of an outer chamber, an inner chamber secured axially in said

outer chamber and terminating adjacent the bottom thereof, tangential gas inlet means at the top of the outer chamber, a first spiral baffle, mounted between said inner and outer chambers, fluid supply means secured about said outer chamber, a fluid supply conduit mounted axially in said inner chamber and associated with said supply means, a second spiral baffle secured between said inner chamber and conduit, U-shaped clips carried by the lower end of the inner chamber, means on said second baffle for seating in said U-clips, nozzles transversely disposed in the travel path of the gas and associated with said fluid supply means and said conduit and means to remove separated gas and solids.

2. A gas separator comprising an outer chamber, an inner chamber secured axially in said outer chamber and extending through one end thereof and terminating adjacent the other end thereof, gas inlet means carried by said outer chamber, concentric spiral baffles mounted in said inner and outer chambers, a plurality of fluid supply pipes disposed vertically about said outer chamber and having their upper ends inturned and commonly joined, a conduit associated with said pipes and disposed axially in said inner chamber, said conduit having its upper end secured at the common juncture of the pipes, spray nozzles laterally carried by said supply pipes and disposed radially into said outer chamber, spray nozzles carried laterally by the lower end of the conduit and means to remove separated gas and solids.

3. A gas separator comprising an outer chamber, an inner chamber mounted axially in said outer chamber and extending through one end thereof, said inner chamber terminating adjacent the other end of the chamber, gas inlet means associated with said outer chamber, concentric spiral baffles mounted in said inner and outer chambers, fluid supply pipes vertically disposed and circumferentially spaced about the outer chamber and having lateral spray nozzles extending radially into the outer chamber, said vertically disposed conduit disposed axially in said inner chamber and connected at its upper end to the converging supply pipes, lateral nozzles carried by the lower end of the conduit and means for removing separated gas and solids.

4. The combination of claim 3, wherein said inner spiral baffle is removably mounted in the inner chamber, said chamber having an annular channel formed at its lower end to seat the lower end of the baffle.

5. The combination of claim 4, wherein the lower end of the baffle terminates in flange members detachably received in said channel.

GEORGE L. FOREMAN.
